UNITED STATES PATENT OFFICE.

CHARLES HEYER, OF NEWARK, NEW JERSEY, ASSIGNOR OF ONE-HALF TO
JACOB FITZGERALD, OF NEWARK, NEW JERSEY.

CURTAIN-HOLDER.

SPECIFICATION forming part of Letters Patent No. 700,142, dated May 13, 1902.

Application filed February 1, 1901. Serial No. 45,621. (No model.)

To all whom it may concern:

Be it known that I, CHARLES HEYER, a citizen of the United States, residing at Newark, in the county of Essex and State of New Jersey, have invented certain new and useful Improvements in Curtain-Holders; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to enable a window over which at the inside a curtain, and particularly a lace curtain, has been stretched to be more easily opened or closed, washed, or otherwise manipulated; to secure a simple and convenient device by means of which the curtain may be neatly stretched and held over the said window and yet permit of an easy and convenient partial removal of the curtain to enable access to the window to be gained, as above described; to avoid more perfectly the defacing of the wood-work of the window and the frame, and to secure other advantages and results, some of which may be referred to hereinafter in connection with the description of the working parts.

The invention consists in the improved curtain-holder for windows and in the arrangements and combinations of parts of the same, all substantially as will be hereinafter set forth, and finally embraced in the clauses of the claim.

Referring to the accompanying drawings, in which like letters of reference indicate corresponding parts in each of the figures, Figure 1 is a front elevation of the curtain-holding frame applied to a window. Fig. 2 is a section of parts of the same on line x , the drawing being on an enlarged scale. Fig. 3 is a sectional detail of lower parts of the said frame and window. Fig. 4 is a front elevation showing the curtain applied to the window. Fig. 5 is a section taken at line x' of Fig. 2. Fig. 6 is a section at line x'' , and Fig. 7 is a section at line x''' .

In said drawings, a indicates an ordinary window-frame to which my improved curtain-holder is applied. Said curtain-holder comprises an upper frame b , which is quadrangular in form, having side portions $b' b'$ and top 55 and bottom bars $b^2 b^3$. Said frame b is adapted to fit into or approximately conform to the upper part of the window-frame, lying preferably within the opening thereof. Said upper frame b is preferably made of metal tubes 60 and at its lower corners is perforated at the lower side, the perforations providing openings by means of which the upper arms $c' c'$ of a lower frame-section c may enter and lie telescopically within the side portions $b' b'$ 65 of the said upper frame. Of the said lower frame c the upwardly-extending arms $c' c'$ are arranged within the side portions of the upper frame-section, as above indicated, fitting neatly, so as to slide therein, and are adapted 70 to be set in said upper frame-section by means of set-screws d . The horizontal bar c^2 of the lower section is also provided with a set-screw e or other fastening device, by means of which the complete frame $b c$ may be fastened to 75 the sill, sash, or other portion of the window or window-frame, and thus be held securely within said window-frame. The upper horizontal bar b^2 of the upper frame-section is adapted to lie upon or in hooks or eyes f , 80 fastened to the upper part or head of the frame, so that the frame $b c$ may swing thereon when released at its lower end.

In operation the upper and lower sections are fastened together by means of the set-screws d , above referred to, the frame-sections being adjusted with relation to one another to enable the frame to enter and properly coincide more or less closely with the inside faces of the window-frame a . The frame $b c$ is then covered with lace, the same being sewed thereto in any suitable manner, the frame being preferably first covered with suitable textile fabric h' , by means of which the lace curtain i is prevented from coming into 95 direct contact with the metal, whereby it might perhaps be injured by rust or the like.

The lower part of the curtain, which is attached to the lower section c , is preferably attached or connected to the section-arms c' 100

c' by means of loose rings *g*, adapted to slide on said arms for purposes hereinafter described.

When the frame *b c* is in its normal position, (shown in Fig. 1,) the curtain is stretched taut thereon, and thus displays its ornamental design or texture to great advantage, the particular curtains for which the frames are specially intended generally displaying artistic designs of great merit, and the curtains are consequently of material of expense and value.

When it is desired to gain access to the glass or window to open or close the same, 15 the lower section may be released and raised telescopically with relation to the upper section by releasing the set-screws *d* and bottom screw *e*, or should it be desired to clean the glass of the whole window the bottom screw 20 or catch alone is released from its coöperating catch of the window-frame and the whole frame is swung inward pivotally on the hooks *f* or screw-eyes at the top of the frame *a*. The rings *g*, in connection with the lower 25 part of the curtain and the lower section *c*, permit the upward sliding of the lower section with ease and without injury to the curtain, said rings permitting the arms *c'* to slide therein as the frame-section *c* moves upward 30 and the curtain is gathered into folds.

I prefer to attach to the opposite sides *b' b'* of the upper section, at or near the upper ends thereof, shade-brackets *h*, upon which an ordinary spring-roller and shade may be supported. Said brackets, roller, and shade 35 are thus removable from the window-frame *a*, with the frame *b c*, and preliminary to cleaning the window or opening or closing the same it is not necessary to disarrange the 40 parts or change the relation of the shade to the curtain stretched or arranged upon the swinging frame.

Having thus described the invention, what I claim as new is—

45 1. The combination of a quadrangular frame-section having tubular side portions *b', b'*, and top and bottom bars *b², b³*, said section being perforated at the point of meeting of the side and bottom portions or bars in line 50 with said side portions; a section having arms

c', c', extending telescopically into said side portions, a curtain attached to said sections and adapted to be stretched thereon when said sections are fitted to the window, said curtain below the bottom bar *b³*, being loosely attached 55 to the arms of the lower frame-section to permit said arms to slide within the said side portions, means for holding said frame and curtain within the window-frame and means for holding the sections at the desired adjustment, substantially as set forth.

2. The combination with the window-frame, of a curtain holding and stretching frame constructed to fit the opening of said window, said frame being suspended from hooks attached 60 to said frame and thus removably supported at the top, means for fastening said frame at the lower part, said frame being in sections, the lower one of which is adapted to be removed to permit access, to the window 65 and means for setting one section with relation to the other, and a curtain attached to said frame-sections, the lower part being loosely attached to permit the sliding of the lower frame within the upper frame, substantially 70 as set forth.

3. The combination with the window-frame, of a curtain holding and stretching frame constructed to fit the opening of said window, said frame being suspended from hooks attached 75 to said frame, and thus removably supported at the top, means for fastening said frame at the lower part, and shade-brackets attached to the upper part of said frame, said frame being in sections, the lower one of which 80 is adapted to be moved to permit access to the window, and means for setting one section with relation to the other, the said frame and its shade-brackets permitting the swinging back of the stretched curtain and drawn-down shade without changing the relation of the shade and curtain to one another, substantially 85 as set forth.

In testimony that I claim the foregoing I have hereunto set my hand this 26th day of 95 January, 1901.

CHAS. HEYER.
